(57) **CLAIM**

The ornamental design for a watch, as shown and described.

DESCRIPTION

The patent of application file contains at least one drawing executed in color. Copies of this patent or patent application publication with color drawing(s) will be provided by the Office upon request and payment of the necessary fee.

FIG. 1 is a front elevation of a watch shown with a digital LED display turned on.

FIG. 2 is a back view of the watch.

FIG. 3 is a right side view of the watch.

FIG. 4 is a left side view of the watch.

FIG. 5 is a top side view of the watch.

FIG. 6 is a bottom side view of the watch.

FIG. 7 is a perspective view of the watch showing both the analog face and the LED display.

FIG. 8 is a front view showing the watch where the LED illumination is turned off.

FIG. 9 is a perspective view showing the state where the LED illumination is turned off.

FIG. 10 is a view showing a mode-switched state wherein a date is displayed; and,

FIG. 11 is a second mode-switched state showing a second display.
